SHELF SUPPORT

Earl E. Nofzinger and Oscar E. Norberg, Greenville, Mich., assignors to Gibson Electric Refrigerator Corporation, Greenville, Mich., a corporation of Michigan

Application November 24, 1939, Serial No. 305,768

6 Claims. (Cl. 248—241)

This invention relates to supports for the shelves of a refrigerator or the like, and more particularly to supports having adjustable means thereon for accurately positioning and guiding slidable shelves within a refrigerator.

With present day large scale production methods, it is difficult to maintain an even spacing of the side walls of the linings of different refrigerators of the same rated capacity. Also, there is a tendency for refrigerator shelves to vary slightly in width. As a result, the proper supporting and guiding of refrigerator shelves for sliding movement has become a serious problem. If ordinary supports of the same dimensions are employed in all refrigerator cabinets of like capacity, some shelves will fit too loosely therein, while others may be too tight or cannot be inserted at all.

Accordingly, it is the principal object of this invention to provide a novel shelf support and guide which is fitted with means capable of adjustment in a horizontal direction whereby oppositely arranged supports may be adjusted to compensate for variations in width of different linings, as well as for shelves of various widths.

Another object of the invention is to provide an adjustable shelf support which is simply and economically fabricated.

For a more detailed description of the invention reference is now made to the following specification and accompanying drawing, wherein—

Figure 1 is a fragmentary pictorial view of the lower portion of a refrigerator cabinet and shelf therein in which the invention is embodied;

Figure 2 is a front elevational view of a support such as that illustrated in Figure 1; and

Figure 3 is a cross-sectional view taken on substantially the line 3—3 of Figure 2 and showing the two adjustable guiding devices in different adjusted positions.

Referring now more specifically to the drawing, Figure 1 illustrates a portion of a refrigerator cabinet 10 having a lining 11. The upper part of the cabinet has been broken away and the door removed to show the interior of the cabinet.

Secured to opposite vertical side walls of the lining 11 are a plurality of shelf supports 12 which carry a conventional shelf 13 made up of an outer frame 14 and a plurality of grid bars 15. Preferably four of the supports 12 are employed to hold the shelf 13, two on each side wall of the lining, though more than four may be used if desired. Each support comprises a body portion 16 having a pair of vertically spaced horizontal U-shaped grooves 18 therein adapted to receive the shelf 13. All of the upper grooves in the sup-

ports lie in the same plane, while the lower grooves lie in a different common plane. The shelf 13 may be mounted in either set of grooves to accommodate different sizes of containers either above or beneath it.

It will be apparent that due to variations in the spacing of the side walls of the lining 11, the transverse spacing of the supports 12 may vary. To compensate for such variations, as well as 10 variations in the widths of different shelves, the supports are provided with the adjusting means about to be described and shown in detail in Figures 2 and 3.

Extending completely through the body portion 15 16 from the rear surface 17 of the shelf support 12, and intersecting the grooves 18 therein, are 20 two apertures 19. The ends of the apertures 19 adjacent the grooves 18 are counterbored or otherwise enlarged slightly at 20. An internally and externally threaded sleeve 21 is positioned in each aperture. Each sleeve has an enlarged head 22 at one end located in the respective counterbore 20.

25 A screw 24 having a large cylindrical head 25 is threaded into each sleeve 21. The head 25 of the screw is received in the respective counterbore and the end of the head forms the effective bottom of the groove 18. The head of the screw is adjustable in a direction into and out of the groove 18 by turning the screw in the internal threads of the sleeve. Thus, the effective depth of the groove may be readily varied. Figure 3 shows the screws 24 in two different positions.

35 The end of each sleeve 21 opposite the head 22 extends outwardly from the body portion 16 and through a hole in the lining 11 of the cabinet. A nut 23 threaded onto the last mentioned end of each sleeve 21 serves to clamp the support 12 40 to the lining 11.

By employing supports such as those just described, proper mounting of the shelf 13 becomes a simple matter. The supports 12 are secured to the side walls of the lining by means of the 45 nuts 23, and the screws 24 may then be turned in or out until the heads thereof properly engage the side edges of the shelf. Thus, an accurate fit between the shelf and the supports is assured.

From the foregoing it will be seen that this invention provides novel shelf supporting and guiding means in said adjustment to compensate for variations in lining and shelf widths is easily obtained.

The scope of the invention is indicated in the 50 appended claims.

We claim:

1. A shelf support comprising a body portion having a surface adapted for engagement with a vertical wall of a compartment, said body portion having an aperture therethrough normal to said surface and a horizontal groove extending parallel to said surface and intersecting said aperture, an internally threaded sleeve in said aperture, and a screw threaded stop within said sleeve, said stop having a portion located in said groove and being adjustable axially of said sleeve whereby to vary the effective depth of the groove.

2. A shelf support comprising a body portion having a surface adapted for engagement with a vertical wall of a compartment, said body portion having a horizontal groove therein extending parallel to said surface and an aperture extending through said body portion normal to said surface and intersecting said groove, an internally and externally threaded sleeve in said aperture, a screw threaded stop having a portion within said sleeve and adjustable in a direction into and out of said groove for varying the effective depth of the latter, and a nut threaded onto said sleeve for clamping said support to said wall.

3. A shelf support comprising a body portion having a surface adapted for engagement with a wall of a compartment, said body portion having an aperture therethrough normal to said surface and a horizontal groove parallel to said surface and intersecting said aperture, a stop within said aperture, said stop having a portion located in said groove and being adjustable axially of said aperture whereby to vary the effective depth of the groove, and means in addition to said stop for

securing said shelf support to said compartment wall.

4. A shelf support comprising a body portion adapted for attachment to a vertical wall of a compartment, said support having a groove therein for the reception of an edge of a shelf, means on said body portion for attaching the latter to said compartment wall, and means in addition to said last named means located in said groove and adjustable toward and away from the bottom thereof for varying the effective depth of the groove.

5. A shelf support comprising a body portion adapted for attachment to a wall, said support having a laterally extending horizontal ledge thereon for the reception of an edge of a shelf, means on said body portion for attaching the latter to said wall, and means in addition to said last named means mounted on said body portion adjacent said ledge and adjustable laterally thereof to vary the effective width of said ledge.

6. A shelf support comprising a body portion having a horizontal ledge on one side thereof adapted to receive and support an edge of a shelf, a hollow wall attaching member carried by and extending laterally from the opposite side of the body portion, means associated with the interior of the wall attaching member and the body portion which is adjustable laterally of the ledge to vary the effective width of the ledge, and means associated with the exterior of the wall attaching member for attaching the support to the wall.
